HOISTING MECHANISM

Filed Dec. 31, 1923

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed December 31, 1923. Serial No. 683,614.

This invention relates to hoisting mechanisms.

It has for its object to provide an improved type of hoisting mechanism. Another object 5 object is to provide an improved hoisting mechanism of the double drum type. A further object is to provide improved hoisting mechanism of the double drum type which uses a reversible motor. A still further object 10 of my invention is to provide an improved double drum hoisting mechanism having a reversible type of motor and having means whereby only one drum at a time will be automatically and positively 15 driven, depending upon the direction of rotation of the motor. Another object is to have the drums disposed on each end of the reversible motor. It is also an object of the invention to provide an improved double 20 drum hoist having a reversible motor disposed between the ends of said drums and supported independently thereof. It is also an object to provide a double drum hoist with the motor disposed between the drums and 25 to provide improved gear reduction means between said motor and drums.

In the accompanying drawings I have shown for purposes of illustration one form 30 which my invention may assume in practice.

In these drawings,—

Fig. 1 is a side elevation, partly broken away, to show details of construction.

Fig. 2 is an enlarged transverse sectional view on line 2—2 of Fig. 1.

Fig. 3 is an enlarged sectional view of a fluid controlled valve.

Fig. 4 is a fragmentary sectional view showing the intermeshing motor rotors.

In my improved hoisting mechanism I propose to use a base 1 having a cylindrical clamping member 2 disposed centrally of said base and projecting outwardly therefrom, this clamping member being adapted to receive a hollow cylindrical motor casing 3. This casing is positioned centrally with respect to the clamping member 2, and has an inwardly projecting portion 4 forming chambers within which a pair of reversely rotatable rotors 5 are disposed. These rotors are herein shown as being of the spur

gear type, although any other suitable type of reversible motor may be used, and are rotatably mounted within side plates 6. These plates abut against the shoulders formed by the inwardly projecting portion 4 and are held thereto by any suitable means. One of the rotor shafts projects outwardly through each plate 6 and the description of the means for actuating one drum by said shaft will suffice for both drums inasmuch as the structure is substantially identical.

Mounted upon the outer end of the rotor shaft is a pinion 7 meshing with a gear 8 fixed to one end of a shaft 9. This shaft is rotatably supported at its inner end by the casting 6 and at its outer end by bearing 11. A standard or casing 10 which projects upwardly from the end of the frame 1, is secured thereto by bolts 12, this standard having an end chamber 13. A plate 14 which is mounted on the standard 10 to cover the chamber 13 supports the bearing 11. Also carried by the standard is a bearing supporting portion 15 adapted to support rotatably one end of a sleeve 16 as by bearings 17 while the sleeve is supported at its opposite end upon the shaft 9 as by a bearing 18. Rotatably mounted upon the sleeve 16 is a drum 19 having usual radial flanges 20, the inner one of which has an annular portion 21, a part of which projects over the end of the motor casing upon which it is rotatably supported as by a roller bearing 22. Disposed upon the periphery of the portion 21 is a usual braking surface 23 with which a usual manually operated brake band 24 cooperates.

The reduction gearing between the shaft 9 and the drum comprises a pinion 27 mounted on the outer end of the shaft 9. This pinion meshes with a gear 28 carried upon a shaft rotatably mounted within the standard 10 about a relatively stationary axis and this shaft also carries pinion 29 meshing with a gear 30 secured to the sleeve 16 as by a key 31. Fixed to the inner end of the sleeve 16 and between the inner flange 20 and the outer end of the casing 3 is a radial arm or drum driver 33 carrying on its outer end a spring pressed pawl 34, herein shown as having a

cylindrical recess 35 which is adapted to engage a cylindrical lug on the end of said arm. Cooperating with the pawl 34 is a ratchet 36 formed on the inner side of the flange 21 substantially in the same plane as the braking surface 23. The motor casing 3 and the drum flange 20 cooperate to form a gear casing holding a supply of lubricating oil 48. It will here be stated that the construction of the 10 pawl and ratchet mechanism for driving the right hand drum is substantially the same as the left end ratchet but instead is adapted for driving engagement only upon reverse rotation.

15 In order to control rotation of the motor any suitable fluid control valve mechanism may be employed. In a fluid motor which is reversible, it is customary to control both the supply of fluid and the exhaust by a common valve. In such case, it is a simple matter to reverse the motor by reversing the connections. A typical valve mechanism is shown in Fig. 3. In the position of the valve as shown in Fig. 3, fluid is being admitted 20 through an inlet passage 40 and through a port 41 into a passage 42 (see also Fig. 4) to cause rotation of the motor in one direction. A second passage 43 has at the same time communication with an exhaust passage 44 as by 25 a passage 45 passing around the wall of the inlet passage 40. When it is desired to reverse the operation of the motor, the valve will be rotated until the passages 41 and 43, and 42 and 45 communicate with each other. 30 Thus the actuating fluid will be passed into the passage 43 to allow the motor to be reversely rotated.

In the operation of the device, assuming the motor to be running in a direction to drive 40 the left hand drum, the pinion 7 will drive shaft 9 through gear 8 which in turn will actuate the sleeve 16 as by pinion and gears 27, 28, and 29, 30, respectively. Power is then transmitted from the left hand end of the 45 sleeve 16 to the arm 33 to cause the pawl 34 to engage the ratchet 36 and thereby positively drive the drum. During this interval the pawl for the right hand drum will be slipping over its ratchet, thus permitting the 50 right hand drum to be rotated freely in order to unwind the cable therefrom.

It will thus be seen that I have provided an extremely simple and compact means whereby when the motor is reversed the power 55 will be automatically transferred from one drum to the other. It will also be noted that my device is symmetrical, thus making a well balanced hoist. I have also so enclosed all operating members that they may be easily 60 and permanently lubricated, thus avoiding any excess wear and I can also readily remove the drums without in any way disturbing the motor. By the aid of covers 14 I can readily inspect the gear mechanism contained within 65 the standard 13, such construction thereby

avoiding any waste of time on the part of the operator or repair man in getting at the seat of trouble, if any should arise.

While I have in this application specifically described one form which my invention may assume in practice, it will be understood that this form of the same is shown for purposes of illustration and that the invention may be modified and embodied in other forms without departing from its spirit or the scope 70 of the appended claims.

What I claim as new and desire to secure by Letters Patent is:

1. In a hoisting mechanism, a reversible motor, a winding drum disposed at each end thereof, and driving connections between said motor and drums including a driver member for each drum, said driver members being connected in driving relation with said drums to alternatively drive the latter automatically 85 in accordance with the direction of motor rotation, and driving gearing between the opposite ends of said motor and each of said driver members.

2. In a hoisting mechanism, a reversible 90 motor, a winding drum disposed at each end thereof, and driving connections between said motor and drums including a driver member for each drum disposed between the adjacent ends of said drum and motor, said driver members being connected in driving relation with said drums to alternatively drive the latter automatically in accordance with the direction of motor rotation, and driving gearing between the opposite ends of said motor 95 and each of said driver members.

3. In a hoisting mechanism, a reversible motor, a winding drum disposed at each end thereof and arranged coaxially therewith, and driving connections between said motor and drums including a driver member for each drum, said driver members being connected in driving relation with said drums to alternatively drive the latter automatically in accordance with the direction of motor rotation, 105 and driving gearing between the opposite ends of said motor and each of said driver members.

4. In a hoisting mechanism, a reversible motor, a winding drum disposed at each end thereof, and driving connections between said motor and drums including a rotatable sleeve disposed at each end of said motor and on which the adjacent drum is journaled, a drum driver member carried by each of said sleeves, 115 said driver members being connected in driving relation with said drums to alternatively drive the latter automatically in accordance with the direction of motor rotation, and driving gearing between the opposite ends of said motor and each of said sleeves.

5. In a hoisting mechanism, a reversible motor, a winding drum disposed at each end thereof, and driving connections between said 120

motor and drums including a rotatable sleeve disposed at each end of said motor and on which the adjacent drum is journaled, a drum driver member carried by the inner end of each of said sleeves, said driver members being connected in driving relation with said drums to alternatively drive the latter automatically in accordance with the direction of motor rotation, and driving gearing between the opposite ends of said motor and the remote end of each of said sleeves.

6. In a hoisting mechanism, a centrally located driving motor, a pair of winding drums disposed at opposite ends of said motor and aligned therewith, said drums being rotatably supported at their adjacent ends on said motor, and driving connections between said motor and drums including a rotatable sleeve disposed within and extending through each of said drums and on which said drums are journaled, drum driver members connected to the adjacent ends of said sleeves, said drum driver members being connected in driving relation with said drums to alternatively drive the latter automatically in accordance with the direction of motor rotation, and driving gearing between the opposite ends of said motor and the remote ends of said sleeves.

7. In a hoisting mechanism, a centrally located motor, a winding drum disposed at each end of said motor, and driving connections between said motor and drums including driving shafts projecting outwardly from the opposite ends of said motor, reduction gearing disposed at the outer ends of said drums and connected to said shafts, teeth carried by the inner ends of said drums, and means driven by said gearing adapted to engage said teeth in driving relation.

8. In a hoisting mechanism, a reversible motor having at opposite ends means for driving gearing, a pair of winding drums one disposed at each of said ends and aligned with said motor, drum driver members disposed between the adjacent ends of said drums and motor, said drum driver members being operative to alternatively drive said drums automatically in accordance with the direction of motor rotation, and driving gearing between the opposite ends of said motor and said driver members operatively connected to said gearing driving means.

9. In a hoisting mechanism, a reversible motor having a stationary casing presenting cylindrical bearing surfaces at its opposite ends, a pair of drums one disposed at each of said ends and having its inner end journaled on the respective bearing surface, each of said drums having a winding portion, and driving connections between the opposite ends of said motor and each of said drums including automatic means for alternatively connecting one or the other of said drums in driving relation in accordance with the direction of motor rotation.

10. In a hoisting mechanism, a motor, gear casings disposed at opposite ends of said motor, a rotatable member supported by and extending between each gear casing and said motor, a winding drum journaled on each rotatable member, and driving connections between said motor and each drum including said rotatable member and reduction gearing housed in the respective casings.

11. In a hoisting mechanism, a base frame having a central standard, a motor carried by said standard, gear casings secured to the ends of said frame, a pair of coaxial winding drums disposed at opposite ends of said motor and supported at their remote ends on said casings and at their adjacent ends on said central standard, and driving connections between the ends of said motor and drums including sets of reduction gears housed in and supported by said casings to revolve on stationary axes.

12. In a hoisting mechanism, a base frame having a central standard, a motor carried by said standard and having a casing presenting cylindrical bearing surfaces at its ends, gear casings secured to the ends of said frame, a pair of coaxial winding drums disposed at opposite ends of said motor and supported at their adjacent ends on said bearing surfaces and at their remote ends on said gear casings, and driving connections between said motor and drums including sets of reduction gears housed in and supported by said casings to revolve on stationary axes.

13. In a hoisting mechanism, a reversible motor having a casing presenting cylindrical bearing surfaces at its ends, a pair of coaxial winding drums disposed at opposite ends of said motor and journaled at their adjacent ends on said bearing surfaces, supports for the remote ends of said drums, and driving connections between the opposite ends of said motor and said drums including an automatic clutch device for each driving connection to automatically either drive or not drive the respective drum in accordance with the direction of motor rotation.

14. In a hoisting mechanism, a driving motor, relatively rotatable winding drums one disposed at each end of said motor, means for supporting said drums on said motor, and driving connections between said drums and motor including a rotatable sleeve disposed within each of said drums and rotatable relative thereto, driving gearing between said motor and sleeves and disposed at each end of each of said sleeves, and driving connections extending through said sleeves and connecting the gearing at the two ends thereof.

15. In a hoisting mechanism, a pair of relatively rotatable coaxial rope winding drums, a reversible motor disposed between the adjacent ends of said drums, a pair of rotatable sleeves projecting in opposite directions from the sides of said motor and into said drums,

operative driving connections between said motor and each sleeve including reduction gearing and a shaft, the latter being disposed within the respective sleeve, and means carried by said sleeves for automatically alternatively driving said drums in accordance with the direction of motor rotation.

16. In a hoisting mechanism, a pair of relatively rotatable coaxial winding drums, a reversible motor disposed between the adjacent ends of said drums, a pair of shafts extending in opposite directions from and supported by the sides of said motor, said drums being positioned coaxial with said shafts, a gear carried by each of said shafts adjacent said motor, a motor pinion meshing therewith, and means for driving said drums by said shafts, said latter means including means for automatically alternatively driving said drums in accordance with the direction of motor rotation.

17. A hoisting mechanism comprising a pair of relatively rotatable coaxial winding drums, a reversible motor disposed between the adjacent ends of said drums, a pair of shafts extending in opposite directions from and supported by the sides of said motor, a gear carried by each of said shafts adjacent said motor, a motor pinion meshing therewith, means for supporting a drum on each of said shafts coaxially therewith, and means for driving said drums by said shafts, said latter means including means for automatically driving one drum at a time in accordance with the direction of motor rotation.

18. In a hoisting mechanism, a motor having a casing, a winding drum journaled at one end on the motor casing, and driving connections between said motor and drum including a shaft extending from the motor and driven thereby through gearing, a sleeve surrounding said shaft, said drum and sleeve being provided with cooperating bearing surfaces, gearing connecting said shaft and sleeve, a gear casing for housing said last mentioned gearing and further providing a journal for said sleeve, and clutch connections between said sleeve and said drum.

19. In a hoisting mechanism, a motor, a pair of coaxial winding drums disposed one at each end of said motor and aligned therewith, and driving connections between said motor and drums including shafts extending from said motor at opposite ends thereof and driven thereby, a sleeve surrounding each of said shafts and journaled thereon, said drums being journaled on said sleeves, driving gears between said motor and shafts, driving gears between each of said shafts and the corresponding sleeve, said gears being disposed at each end of said sleeve, and clutch means for connecting said drums to said sleeves.

20. In a hoisting mechanism, a reversible motor, a pair of coaxial winding drums disposed at opposite ends of said motor and aligned therewith, and driving connections be-

tween said motor and drums including shafts extending from said motor at opposite ends thereof and driven thereby, a sleeve surrounding each of said shafts and journaled thereon, said drums being journaled on said sleeves, driving gears between said motor and shafts, driving gears between each shaft and its respective sleeve, said gears being disposed at opposite ends of said sleeves, and means for connecting said drums to said sleeves automatically in accordance with the direction of motor rotation.

21. In a hoisting mechanism, a pair of relatively rotatable coaxial drums having winding surfaces, a reversible motor disposed between the adjacent ends of said drums and having a casing presenting cylindrical drum bearing surfaces at its ends, a pair of shafts extending in opposite directions from and supported by the ends of said motor, said drums being positioned coaxial with said shafts, a gear carried by each of said shafts adjacent said motor, a motor pinion meshing therewith, and means for driving said drums by said shafts, said latter means including means for driving one drum at a time automatically in accordance with the direction of motor rotation.

22. In a hoisting mechanism, a reversible motor having a casing presenting cylindrical bearing surfaces at the ends thereof, a pair of relatively rotatable drums journaled on said casing and having winding surfaces, and operative driving connections between said motor and drums including means to connect one or the other of said drums with said motor automatically in accordance with the direction of motor rotation.

23. In a hoisting mechanism, a reversible motor, a pair of winding drums disposed at opposite ends of said motor and in alignment therewith, and driving connections between the opposite ends of said motor and said drums including an automatic clutch device for each driving connection to automatically either drive or not drive the respective drum in accordance with the direction of motor rotation.

24. In a hoisting mechanism, a reversible motor, a pair of winding drums disposed at opposite ends of said motor and in alignment therewith, and driving connections between the opposite ends of said motor and said drums, each driving connection including an automatic clutch device to automatically either drive or not drive the respective drum in accordance with the direction of motor rotation and reduction gearing between the motor and automatic clutch device, the gearing being disposed at the outer end of the respective winding drum.

25. In a hoisting mechanism, a pair of relatively rotatable coaxial winding drums, a reversible motor disposed between the remote ends of said drums, and driving connections

between said motor and the adjacent ends of said drums including an automatic clutch device for each driving connection to automatically either drive or not drive the respective drum in accordance with the direction of motor rotation, said clutch devices being of opposite characteristic whereby said drums are only alternatively driven in accordance with the direction of motor rotation.

26. In a hoisting mechanism, a pair of relatively rotatable coaxial winding drums, a reversible driving motor disposed between the remote ends of said drums, and driving connections between said motor and said drums including drum driving means alternatively connected to teeth formed on the adjacent ends of said drums automatically in accordance with the direction of motor rotation.

27. In a hoisting mechanism, a reversible fluid actuated motor having intermeshing rotors, a rotor shaft secured to one of said rotors and projecting from both ends of said motor, and a casing presenting cylindrical bearing surfaces at its ends, relatively rotatable drums each having a winding surface and one disposed at each end of said motor and rotatably supported on its adjacent bearing surface, and driving connections between said motor and drums including a pinion secured to each end of said rotor shaft, and gearing connecting said pinions and drums and including means whereby said drums are only alternatively driven automatically in accordance with the direction of motor rotation.

28. In a hoisting mechanism, a reversible motor, a pair of winding drums adapted to be driven thereby, a pair of sleeves extending in opposite directions from said motor on which said drums are rotatably supported, shafts driven by said motor extending through said sleeves, reduction gearing disposed at the ends of said sleeves and connected to said shafts, and an automatic clutch for each of the driving connections between the respective drums and the motor to automatically either drive or not drive the respective drums in accordance with the directions of motor rotation.

29. In a hoisting mechanism, a pair of winding drums, a reversible driving motor disposed between said drums, and driving connections between said motor and said drums including a pair of sleeves extending in opposite directions from said motor on which said drums are rotatably supported, a pair of drive shafts driven by said motor extending through said sleeves, reduction gearing for each drum disposed at the respective outer ends of said drive shafts and connected thereto, a casing for each of said reduction gearings, said sleeves being carried between said gear casings and said motor, and an automatic clutch device for each of said driving connections to automatically either drive

or not drive the respective drums in accordance with the direction of motor rotation.

30. In a hoisting mechanism, a pair of winding drums having internal gear teeth on each of the same whereby they are driven, a reversible motor disposed between said drums, and driving connections between the opposite ends of said motor and the gear teeth on said drums including shafts driven by said motor extending in opposite directions therefrom through said drums, reduction gearing disposed at the respective outer ends of said shafts and connected thereto by pinions, said pinions being coaxial, and an automatic clutch for each of the driving connections to automatically either drive or not drive the respective drum in accordance with the direction of motor rotation.

31. In a hoisting mechanism, a reversible motor having a casing, a pair of winding drums, the inner ends of said drums being supported on said casing, and driving connections between the opposite ends of said motor and said drums including a pair of drive shafts driven by said motor extending in opposite directions from said motor through said drums, reduction gearing for each drum disposed at the respective outer ends of said drive shafts and connected thereto, and an automatic clutch device for each of the driving connections to automatically either drive or not drive the respective drum in accordance with the direction of motor rotation.

32. In a hoisting mechanism, a pair of winding drums, a reversible driving motor disposed between said drums, and driving connections between said motor and said drums including sleeves extending in opposite directions from said motor on which said drums are rotatably supported, a pair of drive shafts driven by said motor extending through said sleeves, reduction gearing for each drum disposed at the respective outer ends of said drive shafts and connected thereto, a casing for each of said reduction gearings, each gear casing providing a support for the respective reduction gearing and the outer ends of the respective drive shaft and sleeve and an automatic clutch device for each of the driving connections to automatically either drive or not drive the respective drum in accordance with the direction of motor rotation.

In testimony whereof I affix my signature. 120
CHARLES F. OSGOOD.
